US00D615704S

(12) **United States Design Patent**
Wonderley et al.

(10) **Patent No.:** US D615,704 S
(45) **Date of Patent:** ** May 11, 2010

(54) **SHAVING RAZOR**

(75) Inventors: **Jeffrey W. Wonderley**, Fort Defiance, VA (US); **Paradee Bunnag**, Waynesboro, VA (US)

D355,049 S 1/1995 Yasui
D365,419 S 12/1995 Kamiya
D381,121 S 7/1997 Shurtleff et al.
D386,821 S 11/1997 Shurtleff et al.
D392,417 S 3/1998 Gray

(73) Assignee: **American Safety Razor**, Verona, VA (US)

(**) Term: **14 Years**

(Continued)

(21) Appl. No.: **29/337,433**

(57) **CLAIM**

The ornamental design for a shaving razor, as shown and described.

DESCRIPTION

FIG. 1 is a front perspective view of the shaving razor, showing the new design;

FIG. 2 is a front view of the shaving razor;

FIG. 3 is a rear view of the shaving razor;

FIG. 4 is a side view of the shaving razor;

FIG. 5 is another side view of the shaving razor;

FIG. 6 is a top view of the shaving razor; and,

FIG. 7 is a bottom view of the shaving razor.
